UNITED STATES PATENT OFFICE

99,161

DESIGN FOR A TEXTILE FABRIC

Moses F. Gantz, Yonkers, N. Y., assignor to The First Textile Corporation, New York, N. Y.

Application November 20, 1935, Serial No. 59,661

Term of patent 3½ years

To all whom it may concern:

Be it known that I, Moses F. Gantz, a citizen of the United States, residing at Yonkers, in the county of Westchester and State of New York, have invented a new, original, and ornamental Design for a Textile Fabric, of which the following is a specification, reference being had to the accompanying drawing, forming part thereof.

The figure of the drawing is a plan view of a fabric showing my new design.

The design presents an all over crinkled appearance substantially as shown in the drawing.

I claim:

The ornamental design for a textile fabric as herein shown and described.

In testimony whereof, I hereunto affix my signature.

MOSES F. GANTZ.
